UNITED STATES PATENT OFFICE

109,331

DESIGN FOR A METAL BEVERAGE BOTTLE

Charles E. McManus, Spring Lake, N. J., and Amos Calleson and Edgar A. Calleson, Merrick, N. Y., assignors to Crown Cork & Seal Company, Inc., Baltimore, Md., a corporation of New York

Application June 23, 1937, Serial No. 70,026

Term of patent 14 years

To all whom it may concern:

Be it known that we, Charles E. McManus, of Spring Lake, New Jersey, Amos Calleson and Edgar A. Calleson, of Merrick, New York, citizens of the United States, residing at Spring Lake, county of Monmouth, State of New Jersey, and Merrick, county of Nassau, Long Island, New York, respectively, have invented a new, original, and ornamental Design for a Metal Beverage Bottle, of which the following is a specification, reference being had to the accompanying drawing, forming a part thereof.

Figure 1 is a top plan view of a metal beverage bottle showing our new design, and

Figure 2 is a side elevational view.

The design consists of a cylindrical body in

height slightly exceeding its diameter, presenting a short squat-like appearance, said body surface curving and merging continuously with the surface of an integral conical top approximating one-third the height of the body and terminating in an integral, relatively short neck of approximately one-fourth the height of the conical top, said neck having an external rounded bead to be engaged by the skirt of a closure.

We claim:

The ornamental design for a metal beverage bottle, substantially as shown and described.

CHARLES E. McMANUS.
AMOS CALLESON.
EDGAR A. CALLESON.
